UNITED STATES PATENT OFFICE.

JOHN T. SIMPSON, OF NEWARK, NEW JERSEY.

BUILDING CONSTRUCTION.

1,423,161.

Specification of Letters Patent.

Patented July 18, 1922.

Application filed February 1, 1918. Serial No. 214,836.

To all whom it may concern:

Be it known that I, JOHN T. SIMPSON, a citizen of the United States, residing at Newark, in the county of Essex, State of New Jersey, have invented a certain new and useful Improvement in Building Construction, of which the following is a specification.

My invention relates to building construction, and more particularly to composite buildings wherein the load carrying members are composed of reinforced concrete and which consists of shop cast and field made elements, and the surface members of which comprise plastic material backed up by metal lathing or sheathing and a moisture-proof material.

By "shop cast" elements I mean those portions of the structure which may be constructed in a factory and shipped to the point of erection. The shop cast elements are few in number as regards size and configuration and buildings of any size of various types may be built by employing more or less of such elements. These elements are composed of reinforced concrete and may be manufactured in the shop under the very best of conditions. The molds being permanent in character the work may be turned out in perfect shape as regards dimensions, density, disposition of the reinforcements and finish. They may be artificially dried and set and the speed at which they are constructed will be vastly greater than if they were cast on the job and one factory will be able to turn out such elements in sufficient quantities to keep many erecting gangs at widely different points supplied with such material.

By "field made" elements are meant those portions of the building which are constructed at the point of assembly and include the vertical load carrying elements or studs.

The surface elements such as the outside of the structure, the walls, the ceilings, the partitions and the floors are likewise constructed at the point of assembly. Certain of the material employed in such surface, i. e., the lathing or sheathing and the moisture-proof material are factory made and placed in position during the construction of the field cast elements.

The objects of my invention are to provide a structure which will be simple of construction, may be built largely by un-

skilled labor, will be cheap to construct and which by reason of air spaces between the outer surface and the walls will be moisture and frost-proof.

These and further objects will more fully appear in the following specification and accompanying drawings considered together or separately.

I have illustrated one embodiment of my invention in the accompanying drawings in which like parts in all of the several figures are designated by corresponding characters of reference, and in which—

Figure 1 is a vertical sectional view of a wall of a building constructed according to my invention.

Figure 2 is a section on the line 2—2 of Figure 1.

Figure 3 is a section on the line 3—3 of Figure 1.

Figure 4 is a section on the line 4—4 of Figure 1.

Figure 5 is a detail view showing a method of securing the sheathing or lathing to a concrete element.

Fig. 5^a is a detail sectional view, the section being taken at right angles to Fig. 5.

Figure 6 is a detail perspective view of a portion of a shop-cast element.

Figure 7 is a detail view of an anchor or hairpin.

Figure 8 is a front elevation of a building constructed according to my invention with the outer surface removed.

Fig. 9 is a detail sectional view showing a modification, and

Fig. 10 is a detail sectional view showing a modified anchorage.

Referring to the drawings, 1 designates a building constructed in accordance with my invention. The building, as shown in Figure 8 is a two story structure having a door opening 2, window openings 3 and rafters 4 for supporting a hip roof. As shown the building comprises a sill 5 which may be either shop or field cast as desired. The frame of the building, as shown, consists of a skeleton framework of vertical field cast elements or studs 6 and horizontal shop cast element. It will be understood that similar field cast studs are provided in the interior of the building to define the boundaries of the room, hallways, stairways, etc., and to which the walls forming the partitions may be secured.

Certain of the shop cast elements as 7

act as lintels for the doors and windows and others as 8 act as sills for the door and window openings. Other of the shop cast elements as 9 are in the form of struts to properly space and brace the field cast elements and to which the surface coatings may be secured. The rafters 4 are shop cast and the roof may be flat or of any form desired. The floor beams 10 are preferably 10 shop cast.

The shop cast elements are of reinforced concrete and the reinforcements 11, of whatever form they may be, project from the ends of the elements. During the manufacture of the shop cast elements and before the concrete is introduced into the molds anchor members 12, preferably in the form of wire bent to staple or "hair pin" form, are attached to the reinforcements at intervals and pass through the walls of the molds. When the shop cast elements are turned out they will be of reinforced concrete blocks of various sizes and shapes with the reinforcements projecting from the ends thereof and with "hair pins" projecting from the sides.

In constructing the skeleton for the building, the sill 5 is first laid. If the sill be of shop cast elements they will be placed in position in alinement with spaces between their ends and the reinforcements will project into such spaces.

If the sills are to be field cast a mold or molds defining such sills will be placed in position and reinforcements will be properly positioned in the mold and hair pins will be attached to the reinforcements at intervals and project through the walls of the molds. Vertical molds will be erected at intervals on the field cast sill molds or at the joints between the elements of the shop cast sills, when used, and vertical reinforcements with hair pins attached will be positioned in the vertical molds. Floor beams 45 will be positioned projecting into the sill molds or into the spaces between the shop cast sill elements. It will be understood that sills similar to 4 will be positioned throughout the space occupied by the same 50 to support the partition studs.

The molds are now filled with concrete to the desired level. The shop cast struts are now placed in position with their ends overlapping the walls of the molds and with 55 their reinforcements projecting into the molds. Concrete is now poured into the molds embedding the ends of the struts and the projecting reinforcements. This operation will be repeated until the level of the 60 next floor is reached.

When the field cast elements have reached the height of the first floor the shop cast floor beams for the next story are placed in position with their ends resting on the 65 top of the studs thus far cast and with their

reinforcements projecting into the space above the studs so far cast. A shop cast reinforced concrete member 13 is now placed in position between the ends of the floor beams where they rest upon the studs. 70 Other members 13 are placed in position parallel to the beams where they are parallel to the walls of the completed structure. The members 13 will form a ribbon entirely around each room of the building and will 75 project slightly inside of the inner face of each vertical field cast element for a purpose to be hereinafter specified. The reinforcements of the members 13 project from one face of the members near the ends thereof into the spaces in which the studs are to be formed. Projecting from the lower edges of the members are hair pins 14 which are engaged with the reinforcements of the members.

When the floor beams and ribbon are in place the molds of the studs are extended to the level of the next row of shop cast members and concrete is introduced therein to such level embedding the ends of the 90 floor beams and then projecting reinforcements and one side of the ribbon and the projecting ends of the reinforcements of its members.

The work will proceed as before until the 95 ultimate height of the building is reached. The rafters 4 are then placed in position with their ends resting on the tops of the studs thus far cast, the stud molds are extended to the level of the tops of the rafters 100 and concrete is introduced filling the molds to the top and embedding the ends of the rafters and their projecting reinforcements.

Hooks 15 are attached to hair pins projecting from the lower face of the window 105 sills 8 for a purpose to be hereinafter specified.

When the field cast elements have become dry and set the molds are removed and the frame of the building is finished and 110 in position to receive the outer surface 16, walls 17, ceilings 18, floors 18^a and roof. The above mentioned exposed surfaces are all constructed in the same manner except as to the plastic material employed.

A metal lathing or sheathing 19 is secured to the outer and inner faces of the studs 6, lintels 7, sills 5 and 8 and struts 9. A sheet 20 of water-proofed felt or other moisture resisting material is placed in position between the member 19 and the frame element but this sheet 20 may be omitted, if desired. That portion of the lathing 19 at the tops and sides of the door and window openings is bent inward as at 21. The sheet 120 20 may be secured to the frame before the lathing or it may be secured to the latter during or after the manufacture of the same.

The sheathing 19 may be of any desired 130

construction, but I prefer to employ a metal lathing, the material of which is slit at intervals and the material between slits is pressed outward alternately on each side of the plates. At certain parts of the plates, forming the lath, the metal is pressed upward to form ridges 22 to space the body of the lath from the sheet 20 when used or from the framework when the sheet is omitted.

The lathing is secured in position by passing the hair pins 12 through the slits in the former and twisting the legs of the hair pin together around the material of the lath. The hair pins 14 projecting from the underside of the ribbon 13 are secured to the edges of the ceiling lath to retain the same in position between the floor beams 10 and at those portions of the frame parallel to the floor beams. The hooks 15 carried by the hair pins in the lower side of the window sills are engaged with the lathing to support the latter at those points and the hair pins projecting into the door and window openings will support the bent in portions of the lathing at those points. The ridges 22 extend horizontally of the framework and brace the lathing or sheathing between the studs 6.

Stucco is now applied to the exterior lathing to form the weathering surface 16. Concrete is spread over the lathing on the tops of the floor beams and rafters and uniting with the lathing will form reinforced concrete floors and roof. Plaster is applied to the interior lathing to form the walls and ceilings.

The ridges 22 will produce air spaces between the field cast elements and the lathing proper. These air spaces will surround the entire building and effectually prevent the entrance of moisture and frost and prevent radiation of heat from the building. The air spaces between the ceiling and floors will prevent the passage of heat therethrough and will also act to prevent the passage of sound.

The ridges on the floor, wall and ceiling lathing or any of them may be dispensed with if desired and ordinary metal lathing or sheathing may be used at these points. In this construction the air space formed by the ridges 22 of the stucco surface will be relied upon to insulate the interior of the building. This construction may be desirable in mild, dry climates. If desired the ridges 22 may be omitted and the lathing or sheathing placed directly against the studs with or without the felt sheet 20.

The number of shop cast elements is small as regards size and shape and building of many different sizes and types may be constructed with the use of a greater or smaller number of such elements. In the building illustrated six patterns of shop cast ele-

ments are employed and this number may be reduced by casting the ribbon members 13 and studs 9 on the job.

If desired the entire frame of the building may be composed of shop cast elements 70 with projecting reinforcements and grouted together at the points of intersection of the members. By this construction the only field made portions of the structure will be the floors, walls, ceilings and those portions 75 exposed to the weather.

In Fig. 9 I show a modification in which my invention is employed in connection with a sheathing of a well known make. This sheathing is manufactured by arranging longitudinal wires 22^b and transverse wires 22^a on opposite sides of a sheet of tarred felt and electrically welding the wires together through small holes previously punched in the felt at each point where the 85 wires cross. A horizontally arranged spacer 23 is placed in position between the sheathing and the framework. The spacer may or may not be secured to the sheathing. If desired a sheet 20^a of felt or other suitable 90 material may be positioned between the spacers and the studs. With this construction, the air spaces will be defined by sheets of moisture proof material.

The "hair pins" instead of being looped around the reinforcements may be embedded as shown in Fig. 10. When this construction is employed a rod or wire may be passed through the loops of the "hair pin" outside of the sheathing or the loops may 100 be bent down over the sheathing members.

In accordance with the provisions of the patent statutes I have described the principle of my invention together with the apparatus which I now consider to represent 105 the best embodiment thereof, but I desire to have it understood that the apparatus shown is merely illustrative, and that the invention may be carried out in other ways.

Having thus described my invention what 110 I now claim as new and desire to secure by Letters Patent, is:

1. A structure comprising field cast reinforced concrete elements and shop cast reinforced concrete members united to form a 115 monolithic framework, metal lathing, waterproof material between the lathing and framework, spacers disposed between said material and said lathing, and connecting wires embedded in said framework, anchored 120 to the reinforcements thereof, and extending therefrom to extend through the lathing and material to securely anchor such lathing and spacers in position.

2. A structure comprising field cast concrete elements and shop cast concrete members united to form a monolithic framework, reinforcement rods formed in said framework, metal lathing, a waterproof material arranged parallel to the lathing, 130

spacers disposed between said material and said lathing, and connecting wires embedded in said framework, looped around said reinforcement rods and having their free ends projecting therefrom to extend through the lathing and material, the ends of said wires being secured together to securely anchor the lathing and spacers in position.

3. A structure comprising field cast reinforced concrete elements and shop cast reinforced concrete members united to form a monolithic framework, metal lathing or sheathing secured to the exterior of the framework, ridges being formed in said lathing to space the lathing from the framework connecting wires being embedded in said framework and extending therefrom to extend through the lathing, the projecting ends of the wires being secured together to securely anchor the lathing and spacers in position, and a plastic material secured to the lathing or sheathing on the side of the same opposite the elements and a sheet of water-proof material between the plastic material and the framework.

4. A structure comprising field cast reinforced concrete elements and shop cast reinforced concrete members united to form a monolithic framework, metal lathing or sheathing secured to the exterior of the elements, a spacing member between the lathing and the elements, stucco applied to the side of the lathing to inclose the space between the lathing and the member, metal lathing or sheathing secured to the opposite sides of the elements, a sheet between the lathing and the elements, ridges expressed from the lathing to space the lathing from the elements, connecting wires embedded in said framework and extending therefrom to extend through the lathing to secure the

lathing and spacers in position between the same and the sheet.

5. A structure comprising field cast reinforced concrete elements and shop cast reinforced concrete members united to form a monolithic framework, ceiling lathing or sheathing, spacing members, a sheet of water-proof material between the lathing and the framework, and connecting wires embedded in the framework and extending therefrom to extend through the sheet and lathing to secure the lathing and spacing members in position, wall lathing, a sheet of water-proof material between the wall lathing and the framework, other connecting wires embedded in the framework and having looped ends extending therefrom, hooks supported by said looped ends attached to said wall lathing to anchor the same in position, and plastic material applied to said lathing to form the ceiling and walls of said structure.

6. A structure comprising field cast reinforced concrete elements and shop cast reinforced concrete members united to form a monolithic framework, wall lathing, a sheet of water-proof material between the lathing and framework, connecting wires embedded in the framework and having looped ends extending therefrom, hooks linked to said looped ends and attached to said wall lathing to anchor the same in position, and plastic material applied to said lathing to form the ceiling and walls of said structure.

This specification signed and witnessed this 31st day of January, 1918.

JOHN T. SIMPSON.
